ATTORNEY

UNITED STATES PATENT OFFICE

ERNST W. F. HERRMANN, OF SAN ANTONIO, TEXAS

PLUNGER

Application filed September 17, 1928. Serial No. 306,377.

This invention relates to plungers.

An object of the invention is the provision of a resiliently supported cup-shaped plunger which may be of any suitable material for the purpose, and in which the resilient member is employed for maintaining the shape of the material at all times.

Another object of the invention is the provision of a plunger cup formed of leather or some suitable composition material in which is mounted a resilient member adapted to counteract the shrinkage or deformation of the cup, which is usually caused by heating when the plunger is reciprocated within the cylinder, the resilient spring member being adapted to compensate shrinkage while retaining the walls of the cup member in neat contact with the walls of the cylinder.

A further object of the invention is the provision of a plunger in which a flexible cup-shaped member cooperates with a metal disc to form a plunger, a continuous spring member being supported in protective relation with the cup-shaped member for normally maintaining the flanged walls of the said member in close association with the walls of the cylinder in which the plunger or piston is operated.

This invention will be best understood from a consideration of the following detailed description in connection with the accompanying drawings; nevertheless, it is to be understood that the invention is not confined to the disclosure, being susceptible of such changes and modifications as shall define no material departure from the salient features of the invention as expressed in the appended claim, in which:—

In the drawings:—

Figure 1 is a view in elevation with parts broken away and showing the application of my plunger to a pump,

Figure 2 is a bottom plan view of the plunger constructed according to the principles of my invention,

Figure 3 is a transverse vertical section taken along the line 3—3 of Fig. 2,

Figure 4 is a view in perspective of a metal member which supports the spring element of the plunger.

Referring more particularly to the drawings 10 designates a piston rod having a threaded portion 11 which is received by a perforation in the metal disc 12 and a perforation in a cup-shaped member 13. A 55 spring retaining member 14 has a central passage to receive the threaded portion 11 and is held against the inner face of the cup-shaped member 13 by means of a nut 15 and a nut 16.

The plunger per se is cup-shaped and is formed of leather, rubber, or some form of composition material suitable for the purpose and is provided with depending flanges 20 adapted to normally engage the inner walls 65 of the cylinder 21.

The disc 14 is provided with a central passage 22 to receive the threaded portion 11 of the rod 10 and has a plurality of ears 23 projecting radially from the periphery. The ears 70 have inturned portions 24 forming lips to receive the inner portions 25 of a plurality of convolutions 26 of a spring retaining member 27.

The spring retaining member is formed of resilient wire and is bent to form a plurality of convolutions 26 which engage the inner face of the flange 20 of the cup-shaped member 13. Since the diameter of the disc 14 is somewhat less than the inner diameter of 80 the bottom of the cup-shaped member 13, the convolutions 26 project outwardly and at an acute angle to the vertical, with the free ends of the convolutions in engagement with the inner face of the flange 20 for maintaining 85 said flange in proper shape and in contact with the inner face of the wall of the cylinder in which the plunger is being operated. The ends of the spring member, as shown at 30, are looped over one end of the ears 23 of the 90 inturned portion 24, and are bent inwardly to maintain the spring member 27 in position on the supporting tongs of the disc 14.

The plunger constructed according to the principles of my invention is shown incorporated in an air pump for pneumatic tires in Fig. 1, in which a handle 32 is employed for reciprocating the rod 10, and the piston 13. A tube 33 is connected with the discharge port at the base 34 of the pump for conducting 100

the fluids from the cylinder 21 to some device adapted to be supplied with air. It will be appreciated that the piston may be employed in any type of pump and that the spring retaining member will maintain the cup-shaped member in position and will counteract excessive shrinking of the same.

I claim:—

10 A plunger comprising a metal disc, a cup-shaped member formed of flexible material, means for securing the disc and cup-shaped member together, a second disc within the cup-shaped member, a corrugated resilient member supported by the second mentioned disc and engaging the wall of the cup-shaped member, ears projecting from the second mentioned disc and provided with inturned members to receive the convolutions of the resilient member.
